UNITED STATES PATENT OFFICE

ROBERT CHRISTIANSEN, OF HARBURG-ON-THE-ELBE, GERMANY

STEAM-DISTRIBUTION SYSTEM FOR WOOLF'S PISTON COMPOUND ENGINES

Application filed October 23, 1926, Serial No. 143,644, and in Germany December 21, 1925.

The invention relates to a special kind of valve gear or steam distribution for such piston compound engines which operate without a receiver in such manner that at a crank displacement of 180° or 360° the working steam is conveyed directly from the high pressure cylinder out through the distributing valve into the low pressure cylinder (Woolf's system).

- 10 In engines fitted with the new distribution system the low pressure cylinder is provided as is known *per se* at about the centre of its longitudinal surface circumferentially with slots or openings which are covered by the 15 reciprocating piston except shortly before it arrives at its end position for allowing steam to escape the length of the piston being somewhat less than its stroke. The rest of the steam distribution is carried out by valves. 20 The arrangement is such, that the total amount of steam distribution will be allotted to the valve and to the outlet slots or openings in such way that by the latter one portion of the steam exhaust escapes directly 25 from the low pressure cylinder, while all the other steam distribution, that is admission and exhaust of the high pressure cylinder, the inlet into the low pressure cylinder and the remaining portion of the exhaust from the 30 low pressure cylinder is carried out or governed by a single valve and only one passage at each end of one cylinder, which passage also serves for admission of the steam. This valve eventually is influenced by the regulation or the reversing respectively.

Engines in which the inlet and outlet for the high pressure cylinder as well as for the low pressure cylinder are governed by a common valve, it is true, are known, however, 40 from the known valve gears or steam distribution systems the present invention differs inasmuch as by the latter only one portion of the exhaust steam flows back by the passage into the valve casing. By thus dividing up 45 the exhaust steam of the low pressure cylinder the advantage is gained that the valve and the passages need only be constructed for steam at a pressure when leaving the high pressure cylinder and thus the dimensions of such constructional members need only be small.

Moreover engines are known, in which the reduction of compression necessary for low pressure compound engine cylinders having an outlet slot is secured by providing the cylinder with a plurality of outlet ports. Over such engines the engine of the present invention has the advantage that the castings are much less complicated, and therefore can be manufactured with considerable less cost, and moreover that the large noxious surfaces of the known engines that cause losses of heat are avoided.

Owing to the very simple construction of the one-valve-engine according to the present invention a minimum of noxious surfaces and dead spaces results, and also owing to the favorable dimensions of the exhaust ports as compared with the other ports, engines constructed in accordance with the invention operate on a very small consumption of steam.

In the drawing a diagrammatical section of an engine constructed according to the invention is shown, the valve being constructed by way of example as a piston valve with inner steam inlet.

A is the high pressure cylinder, B the high pressure piston, C the low pressure cylinder, D the low pressure piston, F the valve casing, G the valve having two chambers K.

At H the steam enters from the boiler into the middle chamber of the valve casing F. The passages J connect the high pressure cylinder with the valve casing F, and the passages L the low pressure cylinder with the same casing. E are the outlet ports or openings in the wall of the low pressure cylinder.

The steam inlet or admission is effected from the middle chamber of the valve by way of the passages J into the high pressure cylinder (right-hand side of the drawing), and the conveyance from the high pressure cylinder into the low pressure cylinder is effected by way of the passages J, the valve chambers K and the passages L (left-hand side of the drawing). The steam outlet or exhaust is governed from the low pressure cylinder to one portion by the slots E and to another portion by the passages L, the valve chambers K and the passages M (right-hand

side of the drawing). Thus the high pressure cylinder works with contra-flow of the steam, the low pressure partly with a unaf-
flow and partly with a contra-flow.

I claim:—

- 5 1. A steam distribution system for compound engines comprising high and low pressure cylinders, pistons in said cylinders, a valve casing comprising a high pressure inlet 10 port, one port at each end of the high pressure cylinder, one port at each end of the low pressure cylinder, and an exhaust port at each end of the casing, and a single valve in said casing controlling communication of 15 said high pressure inlet port with each of said high pressure cylinder ports, of each of said high pressure cylinder ports with a corresponding low pressure cylinder port, and of each low pressure cylinder port with a corresponding exhaust port.
- 20 2. A steam distribution system for compound engines comprising high and low pressure cylinders, pistons in said cylinders, central piston-controlled outlet ports in said low pressure cylinder, a valve casing comprising a high pressure inlet port, one port at each end of the high pressure cylinder, one port at each end of the low pressure cylinder, and an exhaust port at each end of the casing, 25 and a single valve in said casing controlling communication of said high pressure inlet port with each of said high pressure cylinder ports, of each of said high pressure cylinder ports with a corresponding low pressure cylinder port, and of each low pressure cylinder port with a corresponding exhaust port.

In testimony whereof I have signed my name to this specification.

ROBERT CHRISTIANSEN.
